UNITED STATES PATENT OFFICE

HANS SCHEIDEMANDEL, OF MUNICH, GERMANY

DEVICE FOR THE MANUFACTURE OF DOWELED WOODEN BOARDS

Application filed June 1, 1927, Serial No. 195,627, and in Germany May 12, 1926.

The above invention represents a device for the manufacture of dowled wooden boards and has for its main object to avoid the entrance of the dowels into the boards to be joined in an unequal manner. This has been the case very often up to now, especially when the boards were of different hardness in which case the dowels would naturally enter the soft wood more easily than the wood of greater hardness.

The device in question is based principally upon an arrangement by means of which the dowels are brought between the boards to be joined by a kind of clamping tongs and are held in this position, so that the dowels cannot be pushed out of the tongs during the first part of the compressing of the boards, and consequently will penetrate the boards equally independent of the hardness of the wood.

Following is the specification of the device, which is illustrated in the accompanying drawings. Of the latter Fig. 1 represents a section through A B of Figure 2; Fig. 2 is a plan of Fig. 1; Fig. 3 a side-elevation of Fig. 1; Fig. 4 a plan of the dowel casing on an enlarged scale; Fig. 5 is a part of the side elevation of Fig. 4, Fig. 6 a part of a front elevation according to Fig. 1 on an enlarged scale with hookup. Fig. 7 represents another type of the device for placing the boards upon the working base, shown on reduced scale; Fig. 8 is a plan of Fig. 7.

Fig. 4 shows a dowel casing 1, which is tapered towards the bottom end and provided with a slot of emersion 2, in front of which a guided slide piece 3 is movably attached. The latter is one shank of a pair of tongs, the other shank 4 of which is linked to the upper end of the slide piece 3 by means of a hinge. The bite of the tongs is marked with the number 6. The width of the slide piece 3 is made to correspond with the length of the slot of emersion 2, in consequence of which the latter is entirely covered by the slide piece. The thickness of slide piece 3 is reduced on its upper end, making that way a thin piece 7, of which the width corresponds to the width of the other shank 4 of the pair

of tongs. Shanks 8 and 9 are linked to both sides of piece 7, the shanks supplementing in upturned position piece 7 in regard to the width of slide piece 3, the bite of tongs 6 having notches 7' and 8' extending to both sides. The guidance of the slide piece is brought about by rails 10, the upper ends of which are bent. Shank 4 of the tongs is worked by a pressure bar 11, which is linked to an arm 12 of the slide piece 3 and removed from the slide piece 3 by the pressure of a spring 13. The free end of the pressure bar 11 is working in a reciprocating sense on a rigidly controlled pressure table 15 by means of a travelling ball 14. The figure shows the upper position of the slide piece; the lower position being marked by dotted lines; the side elevation according to Fig. 5 shows the lower position.

The operation of the device according to Figs. 4 and 5 is the following:

A dowel 16 lying in the bite of the tongs in the upper position is held clamped by way of the pressure, transferred through the table 15 on the pressure bar 11 upon the shank 75 of the tongs 4. The shanks 8 and 9 of the slide piece 3 which are swung out thereby by their own weight are lying on the face of arm extension 12, so that dowel 16 projects one third of its length on both sides of the bite 80 of the tongs. Now, when the table moves downwards in the direction of the arrow 18, the pressure bar 11 will swing out in the direction of the arrow 19 worked by the spring 13, thereby releasing the shank 4 of the tongs 35 through its upper lever. Influenced by its own weight, the shank 4 will swing down in the direction of arrow 19', releasing thereby the dowel 16. The slide piece 3 then moves by means of a spring 20 down along the guiding rails 10 as much as is required, whereby the shanks 8 and 9 are caught by the rails and swung up into the plane of the slide piece 3. As soon as the bite of tongs 6 and the notches 7' and 8' arrive at the side of the slot of emersion 2, a new dowel will take the place of the previous. Also in this position of the slide piece the slot of emersion 2 of the casing will be absolutely shut off thereby through the shanks 8 and 9. During the following up- 100

ward motion of the pressure table 15 the slide piece 3 is transferred from the position, shown in dotted lines, into the position drawn in full lines, whereby the newly received dowel 5 is clamped into the bite of the tongs 6 by means of the pressure bar 11, whereas the shanks 8 and 9 will drop down upon the arm extension 12, the same time releasing the parts of the dowel, which correspond to their width. The upward motion of the slide piece 10 is limited through the spring 20 and its counter-hold 21 in such a way, that the dowels 16 in the upper position of the table 15 are lying exactly between the boards 22, which are to be joined. The tongs, as will be explained 15 more clearly later on, remain in this position, until the ends of the dowel, projecting from the sides of the bite of the tongs, have entered the wood.

20 Two dowel casings 1' and 1'' of the kind shown in Figures 4 and 5 are arranged, as may be learned from Figures 1 to 3, below the working table which is made of two channel irons 23 on the outside and two channel 25 irons 24 on the inside, and serves as a supporting base for the boards 22 to be joined, in such a way, that each one moves on a rail 25 in the direction of pressure, marked by arrow 26 (Fig. 2). The two rails 25 again 30 are moving on four transverse axles 27, in the direction of the double drawn arrow 28 (Fig. 3), so that the distance between the dowel casings may be altered. It has been arranged that way, so that the distance between 35 the places at which the dowels have to be forced into the boards can be adjusted according to the requirements. Both of the dowel casings 1' and 1'' are worked by means of a rope 30 and pulley 29 through a weight 31, which tends to hold the respective dowel casing in the position drawn in Fig. 1 in full lines. Two sets of four sprocket wheels 36 and 37 are mounted on the shafts 32, 33, 34 and 35, driven by two endless chains 38 and 39. The chains are guided in the two channel irons 23 on the outside and are equipped with three projections 40, arranged equidistantly, which serve, as will be explained 45 later, for placing the boards 22 together. The driving of the chains is effected by means of belt and pulley 41, which are working upon a shaft 45 over cog wheels 42 and 43 and a chain 44. The shaft 45 is connected by means of an electro-magnetic coupling 46 to a shaft 50 47, which works upon a worm wheel 49, mounted on shaft 32, by way of a worm screw. All the sprocket wheels 36 and 37 are arranged, as has already been mentioned, upon the shaft 32. The upper sprocket wheels 36 55 (Fig. 1) are mounted rigidly on the shaft in such a way that they cannot turn. They are placed in frames 50 and 51 (Figs. 1 and 3), the lower ends of which are arranged to serve as bearings for the shafts 33 and 35 of the lower chain wheels 36 (Fig. 1). The frames

50 and 51 are guided on screw spindles 52 and 53, the two spindles being connected by means of a shaft 54 and bevel wheels 55, 56 and 57, 58. Spindle 53 has been elongated to the outside and equipped with a hand-wheel. It is thus possible by turning the hand-wheel, to move the frames 50 and 51 all together with the sprocket wheels 36, which are placed in bearings upon same, perpendicular to the direction of pressure, that is, the direction 70 marked by the double drawn arrow 60 in Fig. 3. Thus the distance between the two chains 38 and 39 can be altered and adjusted in accordance with the actual length of the boards. Pulley 41 rotates shaft 47 and also by means 80 of an electro-magnetic coupling 61, the shaft 62. Shaft 62 is connected to a shaft 65 by means of bevel-wheels 63 and 64, the shaft operating upon worm wheels 68 and 69 through worm screws 66 and 67. The worm 85 wheels are mounted upon shafts 70 and 71, all of which have been provided with cranks 72. The four cranks are connected to the supporting base of the table by means of articulated levers, the free ends of which move to 90 and fro in guiding pieces 74. Table 15 in Fig. 1 is supported by cotters 75, the lower cotted faces of which are constructed as racks 76. The cotters 75 are arranged upon a corresponding bed 77 in such a way that the table 95 always assumes the horizontal position. The cog-wheels 78 which are arranged upon a shaft 79 catch into the racks 76, the shaft being equipped with a hand wheel 80 on its end. By turning the hand wheel, the cotters 75, which support the table 15 may be moved in the direction of the double drawn arrow in Fig. 1, thus allowing a limited changing of the height of the table 15. This is necessary, in order to be able to get the 100 dowels always into the middle of the boards regardless of their thickness.

On the left side of the machine in Fig. 1, two armed levers 83 and 84 are arranged, which can be swung around a shaft 82, the upper arms of these levers being constructed as stops 85 and 86 for the boards 22. The lower arms 83 and 84 lie close to a cross piece 87, supported by bolts 88, which are arranged in the frame of the machine in a movable way and kept in the stop position (in Fig. 6 shown in full drawn lines) by way of buffer-springs. Shaft 82 can be changed in regard to its height by means of bearings 90 (Fig. 3) placed on both ends, and sliding on vertical shafts 91 and 92. Fig. 1 shows shaft 82 in its lower position, in which the stops 85 and 86 are not in the way of the boards. Fig. 6 shows the upper position of shaft 82, in which position the shaft is held by means of a spring-catch 93, catching under a block 94, while in this position. The stops 85 and 86 are stopping the closest lying boards 22. Spring-catch 93 is worked by an electro-magnetic coil 95, which, when excited, will disen- 110 115 120 125 130

gage the spring-catch 93, in consequence of which the shaft 82 drops into the lower position (Figs. 1 to 3). The shaft 82 has been provided besides with arms 96, which cooperate with the pressure table 15 in such a way, that shaft 82 and the same time the stops 85 and 86 at the end of the upwards motion of the table are raised into the stop position, whereby the catch 93 will catch again the block 94, being under the influence of its spring, and hold it that way in this position. The lever 84 has been equipped finally with an arm 97, which cooperates with one arm 98 of a switch 99 in such a way, that the switch 99 will be closed, when the shaft 82 drops down. This switch is placed in the electric circuit I, which operates the chain drive of the electro-magnetic coupling 46. The lever 98 of the switch 99 also cooperates with the table 15 in such a way, that the switch 99 will also be closed when the table moves downwards. The switch 99 is operated also by a second lever 100 cooperating with the lever 84 in such a way, that when lever 84 is 25 swung out in the direction of the arrow 101, the switch 99 is opened through the influence of the power by which the boards 22 are compressed. The switch 99 is mounted on its rotary axis 102 with that great a friction, that 30 it will rest in any position.

In a second electric circuit II, which serves for exciting the electro-magnetic coupling 61 of the table drive, a switch 103 is arranged, which is kept open contrary to the action of a 35 spring 105 through the pressure table 15 in its uppermost position by means of a lever 104. Connected in parallel with switch 103 a second switch 106 has been arranged in electric circuit II, which is closed by the cross piece 87, whenever the levers 83 and 84 are swung out in the direction of arrow 101 through the influence of the pressure effect of the boards. A third switch 107, which serves for controlling the coil 95, has been placed in the current 40 circuit II in parallel connection. Switch 106, switch 107 and the coil 95 are connected in series. Switch 107 has two arms 108 and 109 in forked relation. By means of the lower arm 108 the switch 107 is placed on its stop contact 110 by the downward movement of the table. By means of the upper arm 109 the switch is again opened by the upward 45 movement of the table.

As may be seen especially in Fig. 3, a device has been arranged above the rails 23 and 24, supporting the boards 22, with the object to take up the boards 22, which have been made ready for the next operation. This device is supported by bearing pedestals 111 and 112. In these latter bearing pedestals the bolts 113 are guided in a movable manner, the inner ends being equipped with supporting frames 114. The supporting frames 114 are stayed against the bearing 112 by means of pressure springs. The outer ends of the

bolts 113 are bent down in form of hooks and serve for the grip of the longer arms of the revolving angle levers 116. The axis of rotation of the revolving angle levers is marked with the number 117. The shorter 70 arms 118 of the revolving angle levers cooperate with table 15 in such a way, that, when the table moves up, the angle levers are swung outward and the frames 114 are drawn that far asunder, contrary to the action of the springs 113, whereby the boards 22', lying on the frame, will drop upon the supporting rails 23 and 24. After the table 15 has passed the lever arms 118, the frames 114 will return to the starting position by means of the working power of the spring 113, so that other boards can be placed upon same. The working ends of the levers 118 are constructed as 75 catches 119, which give, when the table moves down, thus avoiding any influence (operation) upon the revolving levers 116. The frames 114 are provided with travelling balls 121 mounted on articulated levers 120; the balls are pressed downwards by means of the springs 122 against the boards 22, which in 80 this instance are to be joined thus preventing the lifting of the boards from their supporting base 23, 24 during the pressure operation.

In the electric circuit III (Fig. 1) of the 95 motor (not shown in the drawing) which drives the belt pulley, a switch 123 is arranged, which must be worked by hand; the lever of the latter is provided with an elongation 124, which cooperates with the projections 40 of the chain 38 in its movement.

The operation of the device according to Figures 1 to 3 and 6 is the following:

At the beginning the dowel casings 1' and 1'' are influenced (operated) by the weights 31 in the position, shown in Fig. 1 in full drawn lines, in which position the dowels, as has been described above, in the discussion of the Figures 4 and 5, are clamped into the space between two boards 22 to be joined, by 100 means of the slide piece 3. In other words, the position of the dowels is in correspondence with the one shown in Fig. 4 in full drawn lines. Pressure table 15 is then in its upper position (Fig. 6). The switches 103, 106 and 107 are open, switch 99 closed. Now, 105 the moment the switch 123 is to be closed, the pulley 41 will start to rotate through the electric motor not shown in the drawing controlled by this switch. Since the switch 99 is closed, the electro-magnetic coupling 46 of the chain-drive has been engaged; thus starting the drive of the sprocket wheels 36 and 37, mounted upon the shaft 32, over sprocket wheels 42 and 43, chain 44, shaft 45, coupling 46, shaft 47 and worm gear 48, 49. 110

The chains 38 and 39 start to move in the direction of the arrow 26 (Fig. 2). The first set of projections 40 of the chains will thereby hit upon board 22 on the right, moving it 115 120 125 130

against the dowels 16, which are clamped into the tongs. Fig. 1 shows one of the dowels 16 in dotted lines; the other dowel cannot be seen in this figure because it is behind the first one. As soon as the board 22 hits upon the dowel 16, the dowel casings 1' and 1'' guided by the rails 25, will move likewise, contrary to the effect of the weights 31, in the direction of pressure (arrow 26) until the dowels hit also upon the left board (Fig. 1). This board together with the dowel casings 1' and 1'' will then move in the direction of pressure, until it hits upon the stops 85 and 86. The resisting force of these stops by virtue of their buffer-springs 89 (Fig. 6) is that great, that the boards are compressed during the further motion of the chains 38 and 39, whereby the parts of the dowels 16 projecting from both sides of the clamping tongs, will penetrate both of the boards equally in consequence of the clamping power of the tongs, holding the dowels. The clamping pressure, exercised upon the boards by means of the projections 40 will finally become that great, that the stops 85 and 86, contrary to the action of the buffer springs 89 will give way and swing out in the direction of arrow 101. The switch 99 will be opened thereby through the lever 100, causing the current circuit of the electro-magnetic coupling to be interrupted and the chains 38 and 39 to stop. At the same time the switch 106 is temporarily closed by cross-piece 87, thereby actuating the electro-magnetic coupling 61 of the table drive, whereby the crank shafts 70 and 71 are started to rotate by means of the power transmitted from pulley 41 through electro-magnetic coupling 61, shaft 62, bevel-wheels 63 and 64, shaft 65 and worm gear 66, 68, respectively 67, 69. The pressure table 15, which up to now had been in its upper position, starts to move down, thereby releasing in the first instance the switch 103 and closing definitely the circuit II of the coupling 61 of the table drive. This has been arranged for the purpose, that, while the stops 85 and 86 are moving back toward the boards through the force of the springs 89 and in consequence of such motion the switch 106 is opened, an interruption of the table drive cannot take place. The instant the table starts to move down, the pressure bars 11, as already has been explained before, will be swung out through the springs 13 in the direction of arrow 19 (Fig. 4), thereby releasing the dowels 16 from the clamping tongs. The clamping tongs, and the slide-piece 3 will move down in order to take from the dowel-casings new dowels for the next operation. After the clamping tongs have left the gap between the boards which still exists, the weights 31 will start their work by pulling the dowel casings back into their starting position (shown in Fig. 1 in full drawn lines). The

table 15, while moving down, will hit at first upon the lower arm 108 of the switch 107, thus closing it. But an exciting of the coil 95 does not take place by reason of this, because the spring-switch 106 has opened itself again after the moving back of the bar 87 and switches 106 and 107 are in series. Next the table 15 will hit upon the lever 98 of switch 99, which will be closed again. The current circuit of the coupling 46 of the chain-drive will be closed again thereby. The chains 38 and 39 start to move again, definitely pressing the two boards 22 upon the stops 85 and 86. When the pressure has become that great again that the stops 85 and 86 swing out in the direction of arrow 101, the switch 99 will be opened a second time by the lever 100, thereby stopping the chain-drive. At the same time the switch 106 is closed once more, thereby exciting the coil 95 temporarily, because the switch 107 is closed too. The coil 95 disengages the spring catch 93, thereby releasing the shaft 82 which drops together with the stops 85 and 86 into the lower position (Figs. 1 and 3). The arm 97 hits thereby upon the lever 98 of the switch 99; the latter will be closed once more and the chain-drive started again; the completed plate, consisting of the two boards 22 is thrown off the work table in the direction of pressure by the projections 40. The pressure table 15 has passed the lower position, starting already on its upward move. It will pass the lever 98 without having any effect upon same, because the latter had been swung out already in accordance with its last position. The pressure table then opens the switch 107 through the arm 109. It next hits the short lever arms 118 of the revolving levers 116, swinging these out in such a manner, that the opposite lying frames 114 are separated from each other and the supply boards 22 previously placed upon the frames 114 will drop upon the supporting rails 23 and 24. After the levers 118 are released by the table, the frames 114 return to their starting position by means of the operating power of the springs 115, ready to take up a new supply of boards. At the end of its upward motion the pressure table finally strikes the arms 96 of the shaft 82 (the lower position of these arms is shown in dotted lines in Fig. 6) thereby lifting the shaft 82 back into its upper position and securing the shaft 82 once more by the spring catch (pawl) 93, since the coil 95 had been already out of current through the automatic opening of the switch 106. At the end of its upward motion the pressure table 15 opens the switch 103 by way of the lever 104, thereby uncoupling shafts 45 and 47. During its upward motion the pressure table 15, as already explained in the discussion of Figs. 4 and 5, had raised the slide pieces 3 of the dowel casings 1' and 1'' and

the tongs while simultaneously clamping the dowels 16 and had transferred the same to the position shown in Fig. 4.

5 The previously working projection 40 of the chain 38 hits now upon the arm 124 of the switch 123, opens this and thereby stops the driving motor of the pulley 41.

The device will then take again its starting 10 position, and the operation can be started over again.

10 The frames 114 for storing the supply of boards 22' for the next operation to follow, need only be used for such boards, which had not been sorted before according to their 15 width. For boards which have been assorted according to their width, the device shown in Fig. 7 will be employed. The supply boards 22' are piled there in storage cases 125, which are provided with templets 126 on the bottom in such a way, that always the undermost 20 board can be shoved out upon the rails 23 and 24. This motion is caused by a bar 127, which, controlled by constrained movement, travels to and fro. During its movement in 25 the direction of the arrow 128 the bar 127 catches the undermost board of each casing 125, proceeding to its outermost position on the right and shoving thereby the boards upon the rails 23 and 24. On its way the bar 127

30 passes over bridges 129', which are loaded by weights 129 and after being released by the bar, will swing back into the position, shown in Fig. 7 in full drawn lines. On its way back in the direction of the arrow 130 the bar 127 is directed through the then open bridges 129' into shunts 131, which form a 35 passage underneath the storage casing 125. On leaving the switches the bar 127 will raise bridges 132, which in consequence of their 40 weight under normal conditions will take the position shown in Fig. 7 in full drawn lines, dropping back into this position after being released by the bar.

45 The undermost boards 22' have in the meantime proceeded into the range of the templets 126, so that these are caught on the next following operating stroke of the bar 127.

50 In the appended claims the term "fixed position" as applied to the dowels is used to indicate that the dowels are so held as to be immovable axially, radially and circumferentially.

I claim:

55 1. An apparatus for the manufacture of doweled wooden plates from boards comprising means for holding said boards in the same plane, means for pressing said boards together, and releasable means adapted to 60 hold a dowel immovable relative to the dowel holding means against the pressure transmitted through the boards and mounted to be shiftable by the boards, as pressed, so that when the dowel has sufficiently penetrated 65 one board it must move therewith to a corre-

sponding distance into the opposing board.

2. In an apparatus for the manufacture of doweled wooden plates from boards, in combination, means for holding said boards in the same plane, means for pressing said boards together, releasable means adapted to hold a dowel immovable relative to the dowel holding means against the pressure transmitted through the boards and mounted to be shiftable by the boards, as pressed, so that when the dowel has sufficiently penetrated one board it must move therewith to a corresponding distance into the opposing board, means independent of the board being joined for removing said holding means from between said boards, and means for completing said pressing operation after said holding means has been removed.

3. In an apparatus for the manufacture of doweled wooden plates from boards, in combination, means for holding said boards in the same plane, means for pressing said boards together, vertically adjustable and horizontally shiftable means for holding dowels between said boards and preventing longitudinal movement of said dowels relative to said holding means during the greater part of said pressing operation whereby said dowels penetrate the boards being joined equally regardless of their relative hardness, means independent of the boards being joined for removing said holding means from between said boards, and means for completing said pressing operation after said holding means has been removed.

4. In an apparatus for the manufacture of doweled wooden plates from boards, in combination, means for holding the boards in the same plane comprising channel bars, chains riding in said channel bars, board engaging means on said chains for moving said boards when said chains are moved, movable stops mounted adjacent said boards and working against the movement of said chains whereby said boards are pressed together, means for restraining the movement of said stops within a given pressure, means for holding dowels in a fixed position between said boards, means for actuating said chains to move said boards together until they contact said dowel holding means whereupon continued movement of said chains moves said movable stops, means operated by the motion of said stops to stop the motion of said chains, further means operated by the motion of said stops for withdrawing said dowel holding means from between said boards whereupon said stops are moved back to their original position by said restraining means, means operated by said withdrawing means for setting said chains in motion whereby the pressing operation is completed and further motion of said chains again moves said stops and the motion of said chains is again stopped, means operated by this second move-

ment of said stops for withdrawing said stops from the plane of the completed plate, and means operated by the withdrawal of said stops for setting the chains in motion again whereby the completed plate is removed from the machine.

5. In an apparatus for manufacturing doweled wooden plates from boards, in combination, channel plates for holding said boards in the same plane, means mounted adjacent said channel plates carrying a board supply, chains riding in said channel plates, board engaging members on said chains for moving said boards when said chains are moved, stops mounted adjacent said boards cooperating with said board engaging members to press said boards together when said chains are moved, said stops being movable in the plane of the boards and perpendicular to said plane, springs for restraining the movement of said stops in the plane of said boards within a given pressure, releasable means for holding said stops in the plane of said boards, means for holding dowels in a fixed position between said boards, a motor, a switch connecting said motor to a source of energy, power transmission means connected to said motor, means connecting said chains to said transmission means whereby said chains are moved and the boards are pressed together until they contact said dowel holding means whereupon further movement of said chains moves said stops in the plane of said boards, means operated by the movement of said stops for disconnecting said chains from said power transmission means, spring means for withdrawing said dowel holding means, means restraining the removal of said dowel holding means from said dowels and for resisting the action of said spring withdrawing means, means for releasing said restraining means, means operated by the movement of said stops in the plane of said boards for connecting said releasing means to said power transmission means whereby said dowel holding means are withdrawn whereupon said stops are spring returned to their original position, means operated by the release of said restraining means for reconnecting said chains with said power transmission means whereby said chains are set in motion and the pressing operation completed whereupon further motion of said chains move said movable stops in the plane of the boards a second time and the motion of the chains is again stopped, means operated by the second movement of said stops for releasing the means holding said stops in the plane of the boards whereupon said stops are withdrawn from said plane, means operated by the withdrawal of said stops for again connecting said chains to said power transmission means whereby the completed plate is removed from said channel bars, means for returning

the aforesaid dowel holder restraining means back to restraining position, means operated by the return of said restraining means to return said stops to the plane of said boards, further means operated by the return of said restraining means for moving new boards from said board supply to said channel bars and to replace said dowel holding means between said boards, and means operated by the continued movement of said chains for opening the said motor switch whereupon the apparatus is ready for another cycle of operations.

6. In an apparatus for the manufacture of doweled wooden plates from boards, in combination, means for holding said boards in the same plane, a dowel container adjacent said boards, an opening in said container for allowing the emersion of dowels, guides mounted adjacent said container, a bar slidably mounted on said guides having clamping jaws on its free end and covering said emersion opening, means for normally holding said bar with its clamping jaws opposite said opening, means for preventing the entrance of more than one dowel into said jaws, pressure means for moving said bar from said opening to the plane of said boards, means connecting said pressure means to one of said jaws whereby the dowel is firmly clamped in the plane of said boards by said pressure means, means for pressing said boards together until they contact said clamping jaws whereby said dowel penetrates each board equally, and means for releasing the pressure on said jaws and removing them from between the boards.

7. In an apparatus for the manufacture of doweled wooden plates from boards, in combination, means for holding said boards in the same plane, means for pressing said boards together, a container for dowels mounted adjacent said boards and provided with an opening for emitting dowels, a slidably mounted bar adjacent said container and covering said opening, a depression in the end of said bar for receiving a dowel from said opening, a hinged member on the end of said bar adapted to hold said dowel in said depression, means for moving said depression with its dowel from said opening to the plane of said boards and means for applying pressure to said hinged member for clamping said dowel and preventing longitudinal movement of the same in said depression during the greater part of the pressing operation, whereby said dowel penetrates the boards being joined equally regardless of their relative hardness.

8. In an apparatus for the manufacture of doweled wooden plates from boards, in combination, means for holding said boards in the same plane, means for pressing said boards together, a container for dowels mounted adjacent said boards and provided

with an opening for emitting dowels, a slidably mounted bar adjacent said container and covering said opening, a depression in the end of said bar for receiving a dowel from 5 said opening, a hinged member on the end of said bar adapted to hold said dowel in said depression, means for moving said depression with its dowel from said opening to the plane of said boards, means for applying 10 pressure to said hinged member for clamping said dowel and preventing longitudinal movement of the same in said depression during the greater part of the pressing operation, whereby said dowel penetrates the 15 boards being joined equally regardless of their relative hardness, and means for releasing the pressure on said hinged member before the said pressing operation is completed, whereby said depression is free to be 20 returned to said opening in the dowel container.

9. In an apparatus for the manufacture of doweled wooden plates from boards, in combination, means for holding said boards in the same plane, means for pressing said boards 25 together, a container for dowels, means for feeding said dowels from said container to the plane of said boards and releasably holding said dowels immovable relative to the dowel holding means against the pressure 30 transmitted through the boards, said means being mounted to be shiftable by the boards, as pressed, so that when the dowel has sufficiently penetrated one board it must move therewith to a corresponding distance into 35 the opposing board, and means for removing said holding means from between said boards.

10. In an apparatus for the manufacture of doweled wooden plates from boards, in combination, means for holding said boards 40 in the same plane, means for pressing said boards together, a container for dowels, means for feeding said dowels from said container to the plane of said boards and releasably holding said dowels immovable relative to the dowel holding means against the pressure 45 transmitted through the boards, said means being mounted to be shiftable by the boards, as pressed, so that when the dowel has sufficiently penetrated one board it must move therewith to a corresponding distance into 50 the opposing board, means for removing said holding means from between said boards and means for completing said pressing operation after said holding means has been 55 removed.

11. In an apparatus for the manufacture of doweled wooden plates from boards, in combination, means for holding said boards in the same plane, means for pressing said 60 boards together, a container for dowels, vertically adjustable and horizontally shiftable means for feeding said dowels from said container to the plane of said boards and releasably holding said dowels immovable relative to the dowel holding means against the 65

pressure transmitted through the boards, means for removing said holding means from between said boards, and means for completing said pressing operation after said holding means has been removed.

In testimony whereof I hereunto affix my signature.

DR. HANS SCHEIDEMANDEL.
